MANICURIST'S HAND REST

Deborah L. McCarty, Kansas City, Mo.

Filed Mar. 16, 1959, Ser. No. 55,001

Term of patent 7 years

(Cl. D86—10)

Fig. 1.

Fig. 2.

Fig. 3.

Fig. 4.

Fig. 1 is a top plan view of a manicurist's hand rest, showing my new design.

Fig. 2 is a side elevational view thereof;

Fig. 3 is a front elevational view as seen from the left of Fig. 2; and

Fig. 4 is a rear elevational view thereof as seen from the right of Fig. 2.

I claim:

The ornamental design for a manicurist's hand rest, as shown.
